United States Patent Office

Des. 226,169
Patented Jan. 30, 1973

226,169

BOTTLE

John J. Bielicki, Wilmington, and Raymond H. Davis, Newark, Del., assignors to American Can Company, Greenwich, Conn.

Filed July 1, 1971, Ser. No. 159,093

Term of patent 14 years

Int. Cl. D9—01

U.S. Cl. D9—116

FIG. 4

FIG. 5

FIG. 1

FIG. 2

FIG. 3

FIG. 1 is an elevational view of a bottle showing our new design;

FIG. 2 is an elevational view looking from the right side of FIG. 1;

FIG. 3 is a bottom plan view;

FIG. 4 is a top plan view; and

FIG. 5 is a sectional plan view thereof taken along line 5—5 of FIG. 2.

We claim:

The ornamental design for a bottle, substantially as shown.
